UNITED STATES PATENT OFFICE.

WILLIAM HENRY MEIXEL AND JESSE LAVERNE MEIXEL, OF YORK, NEBRASKA.

REVERSIBLE WINDOW.

987,903.

Specification of Letters Patent. Patented Mar. 28, 1911.

Application filed May 9, 1910. Serial No. 560,262.

To all whom it may concern:

Be it known that we, WILLIAM HENRY MEIXEL and JESSE LAVERNE MEIXEL, citizens of the United States, residing at York, in the county of York and State of Nebraska, have invented a new and useful Reversible Window, of which the following is a specification.

The object of this invention is to provide an improved construction for reversible windows.

A further object of this invention is to provide improved means for slidably mounting a window sash in a frame.

A further object of this invention is to provide improved means for sealing or bridging the joints between the side margins of a window sash and a frame.

A further object of this invention is to provide improved means for locking a window sash in a frame.

A further object of this invention is to provide improved means for adjusting the bridging and locking mechanism of a window sash relative to a frame containing said sash.

Our invention consists in the construction, arrangement and combination of elements hereinafter set forth, pointed out in our claims and illustrated by the accompanying drawing, in which—

Figure 1 is an inside elevation of a window frame and sashes therein, said sashes equipped with our improved devices. Fig. 2 is a similar view showing both sashes tilted or oscillated into position for ventilation or cleaning. Fig. 3 is a cross-section on the indicated line 3—3 of Fig. 1. Fig. 4 is a vertical section on the indicated line 4—4 of Fig. 3. Fig. 5 is a vertical section on the indicated line 5—5 of Fig. 3. Figs. 6, 7, 8, 9 and 10 are detail views, on an enlarged scale, of the means employed to mount the sash pivotally in a frame. Figs. 11, 12, 13, 14 and 15 are detail views, on an enlarged scale, of the means employed to manipulate the bridging means between a sash and frame. Figs. 16, 17 and 18 are detail views of bridging means employed between a sash and frame.

In the construction and mounting of the devices as shown the numerals 10, 11 designate jambs, 12, 13 vertical face-casings, 14 a header, 15 a head-casing and 16 a sill of a window frame, which frame may vary in construction as desired so long as it retains

the characteristics noted. Stops 17 (one of which is shown in Figs. 1 and 3) are mounted parallel with each other and project downward from the header 14 and extend from the jamb 10 to the jamb 11. These stops 17 are spaced apart a distance equal to the thickness of the upper end of the upper sash of the window.

The window frame preferably is provided with two sashes of ordinary construction. The lower sash comprises stiles 18, 19, an upper rail 20, a lower rail 21 and a pane 22. The upper sash comprises stiles 23, 24, an upper rail 25, a lower rail 26 and a pane 27. The stiles of these sashes are not provided with the usual socket and groove for sash cords inasmuch as they are not designed to be employed with sash cords and weights. The upper rail 20 and lower rail 26 are provided with the usual beveled projections or lips for fitting of such rails together when the window is closed. The upper and lower sashes are mounted, when the window is closed, in parallel vertical planes, the upper margin of the top rail 25 entering between the stops 17 and the lower margin of the bottom rail 21 overlapping downward on the outer marginal face of the sill 16 and the side margins of said sashes are in sliding engagement with or slightly spaced from opposing faces of the jambs 10, 11. The jambs 10, 11 are formed with vertical grooves 28 (one of which is shown in Fig. 3) parallel with and adjacent to the forward margins of said jambs and opening to the faces thereof. These grooves 28 extend from top to bottom of the jambs and at intervals throughout the length thereof are formed seats or depressions 29 (Figs. 3 and 5), which seats or depressions are of greater depth than the grooves. The stiles 18, 19 are formed with grooves 30 parallel with and adjacent to their front faces. The grooves 30 are arranged wholly between the front faces of the stiles and the median vertical lines thereof.

Weather-strips 31 are mounted loosely in the grooves 30 of the stiles 18, 19 and extend from end to end of said stiles. One of the weather-strips 31 (they being of like construction) is shown in Figs. 16, 17 and 18 and will be observed to be constructed of sheet metal of channel form in cross-section, the flanges thereof being of materially greater width than the spacing apart of such flanges. The weather-strip 31 is formed

with a notch 32 at and crossing its center, which notch is formed in the closed marginal portion of said weather-strip. The weather-strip 31 also is formed with registering pin holes 33 in its center at right angles to the notch 32. The weather strips 31 are so mounted relative to the rails that the free margins of the flanges thereof are directed inward toward the bottoms of the 5 grooves 30 and the closed outer margins of said weather-strips are adapted to enter the grooves 28 of the jambs. Metal frames or socket members 34 are mounted in central angular apertures 35 in the stiles 18, 19 and 10 register with the notches 32 of the weather-strips. The frames 34 may be of any desired construction and are secured in the apertures or mortises 35 by screws extending through holes 36 formed in end portions 15 of face plates thereof and seated in the stiles.

Shot-bolts 37 are mounted horizontally and extend through the notches 32 and between the flanges of the weather-strips 31 20 and also extend across the grooves 30 and into the frames 34. Outer end portions of the shot-bolts 37 are adapted to enter at times into seats 29. The shot-bolts are formed with horizontal slots 38 and pins 39 25 are mounted through said slots and through the registering holes 33 in the weather-strips 31. The shot-bolts 37 are formed with stems 40 which are provided with teeth 41 on their lower margins. The teeth 41 are adapted to 30 mesh with pinions 42 journaled in the frames 34. Toothed sectors 43 are fulcrumed within the frames 34 and mesh with the pinions 42. The toothed sectors 43 are formed with handles 44 extending laterally 35 through slots 45 in the face plates of the frames 34. The stems 40 of the shot-bolts are reduced in thickness throughout portions of their lengths and the sectors 43 are spaced from one wall each of the frames 34 so that 40 said reduced portions of the stems may move longitudinally between said walls and sectors. It is the function of the sectors 43, when oscillated by manual force applied to the handles 44, to rotate the pinions 42 and 45 cause said pinions to move the shot-bolts to or fro horizontally. The shot-bolts have two functions: one being to engage the seats 29 and lock the sash against vertical movement; and the other being to act through 50 the slots 38 and pins 39 in moving the weather-strips 31 into and out of the grooves 28 of the jambs. The jambs 10, 11 also are provided with grooves 45 (one of which is shown in Fig. 3) parallel with and adjacent 55 to the grooves 28. Angle plates 46 are mounted in mortises in and embrace outer edges of the stiles 18, 19 midway between the rails 20, 21. The angle plates 46 are secured to the stiles by screws mounted 60 through holes 47 (Fig. 6) in their base mem- 65 bers and seated in the rear faces of the stiles. Flange members 46^a of the angle plates extend partly across side margins of the stiles 18, 19 and are formed with a plurality of holes 48 arranged in annular rows 70 concentric with the centers of said flanges 46^a (Fig. 9). Balls 49 are mounted in the holes 48 and project from both faces of said flanges. Bearing plates 50, 51, each formed with annular raceways, are mounted on opposite sides of the flanges 46^a and are secured thereto pivotally by rivets 52 extending through the centers of said plates and flanges. The bearing plates 50, 51 overlie and with their ball-races engage diametrically opposite points of the balls 49. Semi-elliptic springs 53 are fixed to the outer faces of the bearing plates 51 by means of rivets 54. The springs 53 extend within and longitudinally of the grooves 45 and are compressed normally so as to exercise pressure in opposite directions against the bottoms of the grooves and the bearing plates 51 respectively, which pressure is of sufficient degree to overcome the normal gravity of a 80 sash and hold said sash in any position in which it may be placed manually. The stiles 18, 19 and angle plates 46 articulate on the rivets 52 when manually oscillated in either direction. The jambs 10, 11 also are provided with grooves 28^a and 45^a and the stiles 23, 24 of the upper sash are provided with duplicates of the elements herein previously described as applied to the stiles of the lower sash and operating relative to the 90 grooves 28 and 45. 95

In practical use the sashes normally are mounted between the jambs with the weather-strips 31 extending within the grooves 28, 28^a, the shot-bolts 37 within the seats 29, the handles 44 in their lowermost inclined positions and the semi-elliptic springs 53 in and frictionally engaging the bottoms of the grooves 45, 45^a. In such positions the shot-bolts 37 prevent raising or 100 lowering of either sash; the weather-strips bridge the spaces and prevent the passage of material quantities of air or moisture between the stiles and jambs and also steady the sashes in the window frame. When it is desired to raise or lower either sash the handles 44 are raised sufficiently to cause the intermeshing sectors 43, pinions 42 and teeth 41 to move the shot-bolts toward each 105 other and out of the seats 29. Such operation also releases any outward pressure from the weather-strips 31 which may have been established through the pins 39. Then the sash can be raised or lowered at will, the weather-strips sliding in the grooves 28, 28^a and the springs 53 sliding in the grooves 45, 45^a, according to whichever sash is being manipulated. When it is desired to 110 oscillate either sash as for purposes of ventilation or to clean the outside of the sash or 115 120 125 130

pane, the handles 44 are moved to their uppermost limits and cause the further withdrawal of the shot-bolts 37. Such further withdrawal of the shot-bolts causes the outer 5 ends of the slots 38 to engage the pins 39 and move the weather-strips inwardly out of the grooves 28, 28a and wholly within the grooves 30. Then the sash may be turned 10 manually on a horizontal axis, articulating on the rivets 52. At the same time the sash is being oscillated, it is maintained at any desired elevation by frictional engagement of its springs 53 in the respective grooves of the jambs.

15 We claim as our invention—

1. In a window construction, a frame, a sash, resilient means vertically slidable relative to the frame, to which the sash is pivotally connected, guiding means carried by 20 and movable laterally of the sash for guiding the sash vertically and preventing its pivotal movement, which guiding means comprises weather strips of channel form mounted in grooves in opposite sides of the 25 sash and adapted to engage at times in grooves in the frame, and a means positively operated in both directions for acting on and moving said guiding means, the operated means comprising a shot bolt movable transversely of the weather strip, means 30 for connecting the shot bolt to the weather strip during a portion of its movement, and means for moving said shot bolt manually.

2. In a window construction, a frame, a 35 sash, said frame formed with parallel vertical grooves opening to each side margin of said sash, said frame also formed with angular notches opening to the bottoms of the grooves therein, resilient means vertically 40 slidable in opposite grooves of said frame, to which the sash is pivotally connected, vertical guides slidably mounted in and movable laterally relative to the remaining vertical grooves, of the frame, said sash 45 formed with vertical grooves adapted wholly to receive said vertical guides, and manually operated means carried by the sash for positively moving said vertical guides laterally relative to the latter 50 grooves, said manually operated means formed with an extension adapted to engage in said notches in the frame.

3. In a window construction, a frame, a sash, said frame formed with parallel vertical 55 grooves opening to each side margin of said sash, said frame also formed with angular notches opening to the bottoms of the grooves therein, resilient means vertically 60 slidable in opposite grooves of said frame, to which the sash is pivotally connected, vertical guides slidably mounted in and movable laterally relative to the remaining vertical grooves, of the frame, said sash 65 formed with vertical grooves adapted wholly to receive said vertical guides, and

manually operated shot bolts carried by the sash for positively moving said vertical guides laterally relative to the latter grooves, said manually operated shot bolts adapted to engage in said notches in the 70 frame, said shot bolts also located contiguous to the pivotal conceptions of the sash.

4. In a window construction, a frame, a sash, said frame formed with parallel vertical grooves opening to each side margin 75 of said sash, said frame also formed with angular notches opening to the bottoms of said grooves and spaced vertically, resilient means vertically slidable in opposite grooves of said frame, to which the sash is pivotally connected, vertical guides slidably mounted in and movable laterally relative to the remaining vertical grooves of the frame, said sash formed with vertical grooves adapted wholly to receive said vertical guides, and 80 shot bolts carried by the sash and extending through said guides, means for connecting said shot bolts to said guides for positively moving said vertical guides laterally relative to the latter grooves, each guide formed 85 of a strip U-shaped in cross-section and arranged for engagement by its closed margin with said frame, said shot bolts adapted to engage in the notches in the frame.

5. In a reversible window having jambs 90 formed with vertical grooves and seats in the bottoms of some of said grooves, the combination of a sash formed with vertical grooves, a strip mounted in each groove of the sash and susceptible of movement into 95 an opposing groove of a jamb, shot-bolts mounted in the sash and arranged for travel transversely of and through the strips, engaging devices between the shot-bolts and strips, consisting of transverse pins in the strips extending through longitudinal slots in the shot bolts, said shot-bolts formed with 100 teeth, pinions mounted in the sash and meshing with the teeth of the shot-bolts, and toothed sectors mounted for oscillation in 105 the sash and meshing with the pinions.

6. In a reversible window having jambs 110 formed with vertical grooves, the combination of a sash formed with vertical grooves, a strip mounted in each groove of the sash and susceptible of movement into an opposing groove of a jamb, shot-bolts mounted in 115 the sash and arranged for travel transversely of and through the strips, engaging devices between the shot-bolts and strips, consisting of transverse pins in the strips extending through longitudinal slots in the shot bolts, said shot-bolts formed with teeth, frames mounted in said sash, pinions mounted 120 in the frames and meshing with the teeth of the shot-bolts, and toothed sectors mounted for oscillation in the frames and meshing with the pinions, said strips also formed with notches adapted to receive end portions of the frames in the sash. 130

7. In a reversible window, a weather-strip of channel form having a notch in the central portion of its closed margin and having a hole in the central portion of each of its flanges, a shot-bolt formed with a slot, said shot-bolt mounted transversely of the strip and adapted to extend through the notch thereof, a pin mounted through the holes of the flanges and through said slot, and means for reciprocating said shot-bolt.
